UNITED STATES PATENT OFFICE.

WILLIAM R. HILL, OF ROCHESTER, NEW YORK, ASSIGNOR TO SARGENT & GREENLEAF, INC., OF ROCHESTER, NEW YORK.

COVER AND OPERATING MEANS FOR DIALS OF PERMUTATION LOCKS.

Application filed April 13, 1927. Serial No. 183,333.

The present invention relates to permutation locks and more particularly to the type in which a dial is employed to determine the different positions of the spindle. An object of this invention is to so mount the dial that it may be adjusted without the possibility of one at a distance surreptitiously obtaining the combination from the operation of the lock by another having the combination. A further object of the invention is to so mount the knob or operating member that the hand of the operator will not project into the line of vision between the operator and the dial. Still another object of the invention is to provide in connection with the dial a novel means for closing the same against surreptitious operation of the dial.

To these and other ends, the invention consists of certain parts and combinations of parts, all of which will be hereinafter described; the novel features being pointed out in the appended claims.

In the drawings:

Fig. 1 is a front view of the lock;

Figure 2 is a vertical section through the dial and Figure 3 is a front view of the lock with the dial cover removed.

Referring more particularly to the drawing, 1 indicates the dial secured, in this instance, to turn with a cap 3 which is journaled in the bottom plate 4 of the housing and is secured to the lock spindle 5. Also mounted to turn on the bottom plate 4 is a knob 6, this knob 6 having secured thereto a gear 7 which meshes with a gear 8 arranged to turn with the cap 3 and the dial 1 on the under side of said dial. A housing cover 9 having a surrounding flange 10 abuts the edge of the bottom plate 4 of the housing and is secured thereto, in this instance, by screws 11. This housing cover encloses both the gears 7 and 8 as well as the dial 1, and has an opening 12 through which the knob 6 projects so that the knob may be operated manually from the outside of the housing in order to shift the dial 1. The housing cover 9 also has an opening 13 at the top thereof through which a portion of the dial 1 may be exposed. A pointer or index 14 is provided at the top of the opening to point to the graduations on the dial 1.

With the end in view of closing the opening 13 so that the permutation lock cannot be operated even though the combination

be known, a shutter mechanism is provided adapted to be locked against opening. This shutter mechanism, in this instance, comprises two blades 15 each of which, in this instance, is supported by one of two arms 16 journaled on the bearing 17 on a bottom plate 4 of the housing in rear of the dial 1 and each extending around the edge of the dial to a shutter blade 15. These two arms support the blades 15 so that they may be moved one toward the other to close the opening in the housing cover or they may be moved one away from the other to open the opening 13 and expose the dial. In their open positions, they may be held by a spring detent 18 provided with a nose 19 adapted to enter notches 20 in the two arms and in closed position, the shutter blades may be held against opening by a padlock or other suitable locking device passed through openings 21 formed in forwardly projecting ears 32 extending from the proximate edges of the two blades.

While the spindle 5 is shown as connected to the dial shaft it is apparent that it might be connected to the shaft of the knob 6. In the latter case, the gears 7 may be smaller than the gear 8 in order to speed up the rotation of the dial.

From the foregoing it will be seen that there has been provided a closure for the dial of a permutation lock which is provided with an opening rendering visible only that portion of the dial adjacent the index or pointer, thus making it impossible for one at a distance to view the operation of the dial and thereby surreptitiously obtaining the combination. The operating knob for the dial is located to one side of the dial and connected to the dial by gearing so that the hand of the user in adjusting the dial is not in the line of vision between the operator and the index. A novel means is employed for closing the opening in the housing through a shutter mechanism which may be locked so that the adjustment of the dial to operate the combination cannot be effected except by one having the key to the lock of the shutter mechanism.

What I claim as my invention and desire to secure by Letters Patent is:

1. The combination with a dial for permutation locks, of a knob for turning the dial, a gearing between the dial and the knob, and a housing inclosing the dial and

- the gearing and having an opening through which a portion of the dial is exposed, and also an opening through which the knob projects.
5. 2. The combination with a dial of a permutation lock, of a housing enclosing the dial and having an opening through which a portion of the dial is exposed and a movable shutter mechanism for entirely closing 10 said opening.
3. The combination with a dial of a permutation lock, of a housing enclosing the dial and having an opening through which a portion of the dial is exposed and a shutter 15 mechanism for closing said opening, embodying a movable blade arranged within the housing and having a portion projected through the opening for effecting the movement of the blade.
20. 4. The combination with a dial of a permutation lock, of a housing enclosing the dial and having an opening through which a portion of the dial is exposed and a shutter mechanism for closing said opening, embodying two blades each having an ear projected therefrom through the opening in the 25 housing and provided with an opening.
5. The combination with a dial of a per-
- mutation lock, of a housing enclosing the dial and having an opening through which a portion of the dial is exposed and a shutter mechanism for closing said opening, embodying a blade mounted to swing about the axis of turning of the dial.
6. The combination with a dial of a permutation lock, of a housing enclosing the dial and having an opening through which a portion of the dial is exposed and a shutter 30 mechanism for closing said opening, embodying two blades each having a perforated ear projected through the opening in the housing, and a pivoted arm connected to each blade at the edge of the dial, lying in rear of the dial.
7. The combination with a dial of a permutation lock, of a housing enclosing the dial and having an opening through which a portion of the dial is exposed and a shutter mechanism for closing said opening, embodying two blades each having a perforated ear projected through the opening in the housing, and a pivoted arm connected to each blade at the edge of the dial, lying in 35 rear of the dial, the two arms being mounted to turn about a common axis.

WILLIAM R. HILL.
